UNITED STATES PATENT OFFICE.

JOHN OVERBEKE, OF CLEVELAND, OHIO.

SPRAYER.

1,117,228.

Specification of Letters Patent. Patented Nov. 17, 1914.

Application filed August 6, 1913. Serial No. 763,243.

To all whom it may concern:

Be it known that I, JOHN OVERBEKE, a citizen of the United States, residing at Cleveland, in the county of Cuyahoga and 5 State of Ohio, have invented certain new and useful Improvements in Sprayers, of which the following is a specification.

This invention relates to improvements in sprayers wherein the spraying material is 10 ejected through a nozzle by the action of a piston movable in a cylinder, in which provision is made for mixing certain material contained in the cylinder, with fluid from a connecting source, and ejecting the mixture 15 from the nozzle.

The invention relates particularly to improvements in the type of sprayer for which Letters Patent No. 1,030,119 were granted to me on June 18th, 1912, and it has for its 20 objects the provision of means for overcoming the back pressure on the piston, resulting from the confining of the flow of the mixture through the nozzle, when a fine spray is desired.

25 Another object of the invention is to provide means for regulating the grade of the spray.

I attain these objects by the construction, combination and arrangement of the parts 30 described in the following specification, reference being had to the accompanying drawings forming a part of same, in which—

Figure 1 is an elevation of the improved 35 device. Fig. 2 is a central vertical section. Fig. 3 is a top view. Fig. 4 is an inside view of the bottom cylinder head, showing the central tube in section. Fig. 5 is a section on line 5—5, Fig. 2, and Fig. 6 illustrates, on an enlarged scale, a scattering 40 device used in the nozzle.

Similar characters of reference are used 45 to designate similar parts in the drawings and specification.

Some of the elements embodied in the improved sprayer, and their functions are 50 similar to those described in my former patent. The cylinder 1 for example, is adapted to contain a powdered substance 55 which is mixed with the fluid, the same as in the former patent. The piston 2 acts as a vehicle for the powder, but is actuated in a different manner, as will presently be explained. The pipe 3 performs substantially 60 the same function in the two devices, it being a conductor for the mixing fluid in both

cases. The control of the flow from the pipe 3, however is an improvement on the former means, and the addition of a second cylinder and piston, adapted to coöperate 60 with the piston 2 as a means for overcom- 65 ing back pressure is also a decided improvement. The novel construction of the nozzle, whereby the spray is graded is likewise an improvement over the former spraying de- 70 vice.

The cylinder 1, which is the container 75 for the powder or other material that enters into the mixture, is provided with a head 1^a. The opposite end of the cylinder 1 is fitted 80 into a flanged collar 4^a. A cylinder 4, of 85 larger diameter than the cylinder 1, has one end fitted into the collar member 4^a, and is provided at its opposite end with the head 4^b, on which is an internally threaded 90 stem 4^c so as to permit the device to be attached to a hose, hydrant, faucet, or other 95 suitable source of fluid supply. The pipe 3 is threaded centrally into and through the head 4^b, so that it will be in open commun- 100 ication with the fluid supply. The pipe 3 extends axially through both cylinders 1 and 4. A piston 5 adapted to operate in the cylinder 4, is connected with the piston 2 by the connecting member 6, which in the 105 construction illustrated, consists of a pipe threaded into the two pistons, the pipe 3 extending longitudinally through the connecting pipe 6. The head 4^b is provided 110 with a series of ports 4^d, through which the 115 fluid under pressure, flows into the cylinder 4 and actuates the piston 5, which in turn 120 operates the piston 2, through the medium 125 of the member 6. Openings 4^e are provided 130 in the flange of the collar 4 for the escape- 135 ment of air from the cylinder 4. The piston 2 is provided with a stuffing box 2^a, through 140 which the pipe 3 passes.

In the pipe 3, near the free terminal 145 thereof is a series of apertures 3^a. The head 1^a is provided with an externally 150 threaded stem 1^b, having a central bore 1^c. A threaded cap 7 is adapted to operate on the stem 1^b, and is provided with a sleeve 7^a, which enters the bore 1^c, and is adapted to 155 telescope the pipe 3 at its free end. The function of the cap 7 with its sleeve 7^a, is to regulate the mixing of material from the cylinder 1 with the fluid from the pipe 3, 160 this is accomplished by the screwing up or 165 down of the cap on the stem 1^b, which causes the sleeve 7^a to cover or uncover the

5 apertures in the pipe 3. The apertures are preferably staggered so that certain ones of them may be covered while others are uncovered. The cap 7 is provided with a dial 7^b, for indicating the position of the sleeve. The nozzle 8 is threaded onto the stem 7^c of the cap 7, the bore of the sleeve 7^a extending through said stem. The nozzle is provided with the ordinary adjustable 10 spraying attachment 8^a, and also with a collar 9, and a bracket 8^b. A lever 10 is pivoted to the bracket 8^b. One arm of the lever has a flaring or spoon-shaped terminal 10^a, adapted to operate over the discharge 15 end of the nozzle. The other arm of the lever has a slot therein, through which the shank of a thumb screw 11 passes and is threaded into a boss 9^a, on the collar 9. The lower arm of the lever 10 being held 20 between the collars 11^a, permits of the pitch of the spoon 10^a being regulated by the thumb screw 11.

To more effectually diffuse the ingredients, and assist in the mixing and spraying, 25 a scattering or multiple deflecting member 12 is inserted in the sleeve 7^a. This member is preferably made of thin sheet metal, and consists of a series of vanes 12^a diverging in different directions from the spine. The 30 vanes being thin offer little resistance, and the member fitting snug in the sleeve will be held in position; however it may be attached to the end of the pipe 3, or to the sleeve 7^a if found necessary. The charging 35 of the cylinder 1 with the powdered material, lead arseniate, for instance, is accomplished in the same manner as in the former patented device, referred to, by removing the head 1^a and forcing the piston 2 backward to the limit, after which the cylinder 40 is filled and the head 1^a replaced. In forcing the piston 2 backward, the piston 5 is also pushed to the limit, through the medium of the connecting member 6.

45 In operation, the fluid from the supply source, flows in two separate courses, one stream passing directly through pipe 3, while the other course is through the ports 4^a, and serves to actuate the piston 5, which 50 in turn operates the piston 2, whereupon the material contained in the cylinder 1 is forced through the apertures 3^a into the sleeve 7^a, where it mixes with the fluid flowing through the pipe 3, and is forced 55 through, and ejected from the nozzle in the form of spray of more or less density, as provided for by the adjustment of the nozzle attachments. As a matter of course, when the discharge from the nozzle is reduced, 60 which occurs when the character of the spray is changed the resistance is greater and the consequent back pressure on the piston 2 is increased, thereby necessitating more power to actuate the piston. By the 65 employment of the cylinder 4, of greater

diameter than the cylinder 1, the direct, or primary actuating piston 5 has a greater area than the secondary piston 2, which receives the back pressure direct. While it is true that the back pressure is transmitted 70 from the piston 2, through the connecting member 6, to the piston 5, the greater area of piston 5 overcomes to a certain extent the back pressure, with the result that less power is required to operate the device. 75

The invention may be put to a number of different uses, as, for instance, in spraying trees or plants, applying paint or other material, and for fire extinguishing and 80 infecting purposes.

While it may not be found, in all instances necessary to employ all the elements of the nozzle construction to produce the desired result, I wish it to be understood that they may be combined in one device, or 85 certain ones may be eliminated without departing from the nature of the invention, the limitation being governed by the scope of the claims and the existing state of the art. 90

Having now described my invention, what I claim and desire to secure by Letters Patent is:—

1. A sprayer comprising a pipe having a spraying nozzle at its discharge end; a cylinder communicating at one end with said nozzle; a second cylinder of larger diameter axially connected with the first cylinder; connected pistons arranged in the two cylinders; the pipe passing centrally through 100 both cylinders and the pistons; and a fluid supply connection communicating with the inlet end of said pipe and with the larger of the two cylinders, behind the piston. 105

2. In a sprayer, the combination of a cylinder provided at one end with an outlet and a spraying nozzle connected thereto; a second cylinder of larger diameter connected with the other end; a pipe arranged within, and extending centrally through the cylinders and communicating at its discharge end with the said outlet; connected pistons arranged within the connecting cylinders, and 110 slidable upon said pipe; and means located at the remote end of the larger cylinder for supplying fluid simultaneously to the inlet end of said pipe, and to the interior of said cylinder behind the piston for operating said piston. 115

3. A sprayer comprising a chargeable cylinder; a spraying nozzle in communication with one end of the cylinder; a second cylinder of larger diameter connected with the opposite end of the chargeable cylinder; a fluid supply pipe passing longitudinally 120 through the two cylinders and communicating with the nozzle; a piston arranged within the chargeable cylinder and slidable upon said pipe for discharging the contents of said cylinder into said nozzle, and causing 125

130

- the same to mix therein with the fluid discharged from said pipe; a piston arranged within the second or larger cylinder; connecting means between the two pistons; and means located at the remote end of the larger cylinder for supplying fluid simultaneously to the inlet end of said pipe, and to the interior of said cylinder behind the piston for operating said piston.
- 10 4. In a sprayer, the combination of a chargeable cylinder provided at one end with an outlet and a spraying nozzle; a second cylinder of larger diameter connected with the other end; a head in the remote end of the larger cylinder; a fluid supply pipe extending longitudinally through both cylinders, said supply pipe opening into the nozzle; apertures in the pipe for communication between the interior of said pipe and the chargeable cylinder; means for opening and closing said apertures; a piston arranged within the chargeable cylinder and slideable upon the pipe for discharging the contents of said cylinder; a piston arranged within the second or larger cylinder; connecting means between the two pistons; and means connected with the head of the larger cylinder for supplying fluid simultaneously to the inlet end of the pipe, and to the interior of the said cylinder behind the piston for operating said piston.
- 15 5. In a sprayer, the combination of a nozzle; a pipe adapted to discharge into said nozzle; a chargeable cylinder communicating at one end with said nozzle; apertures in said pipe for communication between the interior of said pipe and the chargeable cylinder; an adjustable sleeve in said nozzle adapted to open and close said apertures; a second cylinder of larger diameter axially connected with the chargeable cylinder; connected pistons in the two cylinders; the pipe passing centrally through both cylinders and the pistons; and a fluid supply connection communicating with the inlet end of said pipe and with the larger of the two cylinders behind the piston, for actuating said piston.
- 20 6. In a sprayer, the combination of a nozzle; a pipe adapted to discharge into said nozzle; a chargeable cylinder communicating at one end with said nozzle; apertures in said pipe for communication between the interior of said pipe and the chargeable cylinder; an adjustable sleeve in said nozzle adapted to open and close said apertures; a second cylinder of larger diameter axially connected with the chargeable cylinder; connected pistons in the two cylinders; the pipe passing centrally through both cylinders and the pistons; and a fluid supply connection communicating with the inlet end of said pipe and with the larger of the two cylinders behind the piston, for actuating said piston.
- 25 7. In a sprayer, the combination of a nozzle; a pipe adapted to discharge into said nozzle; a chargeable cylinder communicating at one end with said nozzle; apertures in said pipe for communication between the interior of said pipe and the chargeable cylinder; an adjustable sleeve in said nozzle adapted to open and close said apertures; a deflecting member inserted in said sleeve; a second cylinder of larger diameter axially connected with the chargeable cylinder; connected pistons in the two cylinders; the pipe passing centrally through both cylinders and the pistons; and means connected with the head of the larger cylinder for supplying fluid simultaneously to the inlet end of the pipe, and to the interior of the said cylinder behind the piston for operating said piston.
